H. W. DAY,
METHOD OF AND APPARATUS FOR APPLYING COATING,
APPLICATION FILED MAR. 12, 1920.

Patented Feb. 15, 1921.

Fig. 1.

UNITED STATES PATENT OFFICE.

HERBERT W. DAY, OF WOLLASTON, MASSACHUSETTS, ASSIGNOR TO SPRAY ENGINEERING COMPANY, OF BOSTON, MASSACHUSETTS, A CORPORATION OF MASSACHUSETTS.

METHOD OF AND APPARATUS FOR APPLYING COATING.

1,368,612.

Specification of Letters Patent. Patented Feb. 15, 1921.

Application filed March 12, 1920. Serial No. 365,347.

To all whom it may concern:

Be it known that I, HERBERT W. DAY, a citizen of the United States, and a resident of Wollaston, in the county of Norfolk and State of Massachusetts, have invented an Improvement in Methods of and Apparatus for Applying Coating, of which the following description, in connection with the accompanying drawings, is a specification, like characters on the drawings representing like parts.

This invention relates to method of and apparatus for applying coating to surfaces, and in its preferred embodiment is an improvement upon the construction disclosed in my Patent No. 1,321,014, dated November 4, 1919.

The coating, if a liquid, may be a paint, japan, varnish or any other suitable coating medium, or it may, if desired, be a solid in powdered form, and the material or surface to which it is to be applied may be of any character, such, for example, as wood, metal or other material.

Referring more particularly to the drawing, wherein I have represented a single embodiment of my invention,—

Figure 1 is a vertical longitudinal section of a tool constructed in accordance with my invention;

Fig. 2 is an end elevation of the tool, looking toward the right in Fig. 1; and

Fig. 3 is a vertical section upon the line 3—3 of Fig. 1, looking toward the right in said figure.

The tool or appliance may be of any suitable material but is preferably metallic and may be of the general form shown in my Patent No. 1,172,233, dated February 15, 1916, or of any other suitable form or construction. The body 1 is, however, preferably provided with a handle or extension 2 integral therewith and provided with a guard 3 inclosing the free end of the valve operating lever 4 pivoted at 5 upon the body 1. In the disclosed form of the invention, the said operating lever 4 is of general trigger form, but such construction may be widely varied within the scope and purpose of the invention.

The handle 2 is provided with a passage 6 for the paint or other suitable coating liquid or powder, which may be supplied through gravity or under suitable pressure

if desired and also with a passage 7 for the air or other suitable fluid under pressure. In the form of tool herein shown, I have represented the passages 6, 7 as pipes suitably secured in the body 1 and as communicating at their inner ends with passages 8, 9 cored or otherwise suitably provided in the body 1. Controlling the paint supply passage 8 is a valve which may be of any suitable form, but which is herein represented as an axially movable piston or plunger 10 positioned within a valve casing 11 and having a stem 12 extending through the valve casing into contact with the operating lever 4, as clearly shown in Fig. 1. The valve here shown as a piston or plunger is normally held seated by a coiled spring 13 surrounding the stem 12 and seated in a recess 14 in a cap 15 threaded at 16 into the body 1 similarly threaded at 17.

The passage 9 for the air is controlled by a similar valve indicated generally at 18 in Fig. 2, the spindle 19 thereof contacting with the valve operating lever 4 which is shaped so as to engage both valves in a manner herein unnecessary more fully to illustrate.

The body 1 is cored to provide a longitudinal passage 20 which is internally threaded at 21, 22 for the reception respectively of a tubular member 23 threaded at 24 and a needle valve 25 threaded at 26. The tubular member 23 at its forward end is preferably suitably formed to permit the passage of the coating material issuing from the valve chamber 10 into the passage 27 and thence into the circumferential space 28. For this purpose, the forward end of the tubular member 20 is preferably squared. Thus the coating material, when the valve 10 is opened, is permitted to flow through the passage 6, the valve casing 11, the passages 27, 28, and thence past the squared formation. Upon the forward end of the tubular member 20 is threaded or otherwise positioned a cap 30, which may if desired be similar to the corresponding member in my Patent No. 1,172,233. The needle valve 25 is seated at its outer end in the cap 30 as indicated in Fig. 1, and the forward end of the said needle valve is guided and positioned by any suitable means, as, for example, by a coiled wire 31 encircling the head of the valve and maintaining it in a

central position when the valve is unseated. The rear end of the valve 25 may be provided with a suitable lock nut 32.

The air passage 9 is in communication 5 with a passage 33 indicated in dotted lines in Fig. 1, which is itself in communication with the valve chamber containing the valve 18 and extending from such valve chamber is an air passage 34 indicated in dotted 10 lines in Fig. 1 and communicating with a passage 35 forming an enlargement of the passage 36 of the tubular member 20. When the valve 18 is opened, the air flows through the passage 33 past the valve 18 15 through the passages 34, 35 and into the passage 36 governed or controlled by the needle valve 25.

Upon the outer end of the body 1 is threaded or otherwise suitably secured a 20 preferably cap-like member 37 herein shown as having a concaved or curved inner surface 38 and a small central opening 39 in line with the axis of the needle valve 25. The length of the threaded portion 40 of 25 the cap like member 37 is sufficient to permit adjustment of the member 37 so as to provide for the effective formation of a film and the variation of the thickness thereof as described in my Patent No. 30 1,172,233. Such film is constantly formed and maintained by capillary action between the surface 38 and the outer surface 41 of the inner cap 30 which are brought close enough together to insure such action. The 35 air entering through the passage 36 breaks through the film at the central portion of the cap and discharges the same upon the work in very fine globules. Said film is constantly broken by the air or other fluid 40 but is constantly restored through the action of capillarity. Hence the coating material may be merely under suction due to capillary action. The maintenance of the supply of coating material is not dependent 45 upon the presence of the air current which is used merely to break the film and discharge the globules. I effect through the described construction a very fine division 50 of the coating material as set forth in my said Patent No. 1,172,233.

The construction of parts thus far described effects the formation of a mass of spray of general conical form issuing through the orifice 39, but generally circular in cross section. This result is effected by the disruption of the film formed 55 between the cap like members 30, 37 through the agency of the air or other suitable fluid in the manner already described.

60 I am aware that it has been proposed to modify the character of the spray issuing from a tool or appliance for applying coating by means of supplemental jets of air directed upon the discharged spray, as

shown, for example, in the patent to Bur- 65 dick, No. 649,430, dated May 15, 1900, and also in the patent to De Vilbiss & Mueller, No. 1,260,522, dated March 26, 1918. In accordance with both of these patents, the shape of the spray discharge is changed 70 from a circular form into that of a thin sheet through the use of supplemental air jets directed upon the spray issuing from the discharge end of the tool or like appliance. 75

As fully set forth in my said Patent No. 1,321,014, I therein provide for discharging supplemental air jets upon the discharged film of paint or other coating material and in such a manner as to change 80 or transform the issuing spray from a conical formation circular in cross section into a sheet. In said patent, I disclosed means and a process whereby a mass of spray as discharged may be given any form in cross 85 section between that of a relatively thin sheet and a cone or mass circular in cross section. I effect this same general result in accordance with my present invention. To that end I provide as broadly disclosed 90 in my said Patent No. 1,321,014, a generally cylindrical member 42 having any suitable number and herein two tubular extensions 43, 44, preferably diametrically opposed to each other and terminating in 95 the discharge passages 45, 46 inclined toward each other and clearly represented in Fig. 1.

The two or other number of supplemental air passages 43, 44 are desirably in constant communication at their inner ends through passages or ports 47, 48 with a completely annular passage or groove 49 shown as formed upon the outer surface of the forward end of the body 1, and indicated also in Fig. 3. 100

As disclosed in my Patent No. 1,321,014, the member provided for the discharge of supplemental air jets was provided with a substantially spherical inner surface adapted 110 to be received upon a correspondingly shaped portion of the body of the tool.

The construction disclosed in this application constitutes an improvement upon that of my said patent in that I guard against all 115 possibility of leakage of the air and even of the coating material due to wear, and I also provide for adjustment of the member 42 longitudinally of the tool, that is, in a direction that will move the terminals of the 120 discharge passages 43, 44 forwardly or rearwardly with respect to the point at which the main compressed air supply and the coating are discharged from the tool. I have discovered in the course of my experimentation that with a given pressure of the 125 supplemental air discharge, a greater breaking up effect is secured upon the coating

material by advancing the point at which the supplemental air impacts upon the discharged mass of coating material; that is to say, by advancing said point forward 5 with respect to the point of discharge of the coating material from the tool, I discharge the supplemental air jet or jets upon the discharged coating material at a point where the main discharged air supply has slightly 10 spent its force and where the supplemental air jets are thus permitted with a given pressure to break up and transform the shape of the discharged mass of coating material more effectively. Thus by advancing 15 the point or points of supplemental air discharge, I may discharge the air supplementally under less pressure and secure the same breaking up effect that would be secured with a greater pressure and with the 20 points of supplemental air discharge at a more rearward position. Therefore, I am enabled in the practice of my invention and in accordance with my process to vary the breaking up effect produced by the supplemental 25 air discharge by varying the point at which such supplemental air discharge impinges upon the discharged coating material, such point being varied in a to and fro or longitudinal direction with respect 30 to the longitudinal axis of the tool.

Preferably I accomplish this result by providing the surface of the body 1 with a thread 50 which is preferably both in advance of and in the rear of the annular passage or groove 49. I also provide a thread, 35 as indicated at 51 upon the inner surface of the cylindrical member 42 both in advance of and in the rear of the openings or ports 47, 48 therein.

40 The annular passage or groove 49 is of such diameter that a substantial longitudinal adjustment is permitted of the member 42 without destroying the air communication between the ports 47, 48 and the annular passage or groove 49. Desirably I make 45 the annular groove or passage 49 of considerable width for this purpose, and the ports 47, 48 may be and desirably are somewhat elongated in the direction of the longitudinal axis of the member 42. The threads 50, 51 provide for a very close union 50 between the member 42 and the body 1 and yet of a character permitting the very ready adjustment of the member 42.

55 The annular passage or groove 49, and hence the passages 43, 44 are in communication with the longitudinally extending passage 52 and the communicating passage 53 of the body 1, such passage 53 being in communication with the main air passage 35 through a small port 54. This port is controlled by a valve 55 threaded into an opening 56 of the body 1 and preferably having a knurled head 57 by which it may be readily

turned manually as disclosed in my said 65 Patent No. 1,321,014. The inner tapered end 58 of said valve is adapted to be seated so as to close the port 54 or to be opened fully or to any desired extent, thus regulating the air supply through the passage 53. 70 This valve is in effect a reducing valve whereby the supplemental air pressure can be regulated, and whereby any desired degree of fineness of the discharged coating material may be obtained. 75

It will be evident that the annular passage or groove 49 may if desired be formed in the inner surface of the member 42 and that the openings 47, 48 may be provided in the body 1. It will be understood from 80 the foregoing description that the supplemental air passages 43, 44 are in constant communication with the annular passage or groove 49 whatever be the circumferential position of the cylindrical member 42, that 85 is, provided the member 42 has not been adjusted far enough longitudinally in a forward direction with respect to the point of discharge of the coating material to cut off such communication. Desirably I do not 90 interrupt or cut off the discharge of the supplemental air jets by movement of the cylindrical member 42 longitudinally of the body 1, but do this wholly through manipulation of the valve 55. The purpose of the 95 longitudinal adjustment of the member 42 is to vary the point at which the supplemental air jet or jets is or are permitted to impact upon the discharged coating material with the results and advantages herein- 100 before set forth.

My invention in its broadest application is not limited to the formation of a film of the coating material, since such coating material may be positioned with respect to the 105 discharging motive fluid in any suitable manner. Preferably, however, I provide for forming, breaking through and discharging the film.

It will be observed that the member 42 is 110 capable not only of longitudinal adjustment for the purpose set forth, but is mounted for circumferential or rotary movement upon the body 1, so as to secure any desired plane of the sheet of coating material and to maintain such plane thereof. Both the longitudinal and the rotary or circumferential adjustments are secured without the necessity of interrupting the communication between the supplemental motive agent discharge passages of the member 42 and the motive agent supply passage of the member 1. 115 120

Having thus described one illustrative embodiment of my invention and the method 125 of practising the same, I desire it to be understood that although specific terms are employed, they are used in a generic and de-

scriptive sense and not for purposes of limitation, the scope of the invention being set forth in the following claims.

Claims:

5. 1. That method of applying coating comprising providing a film of coating material, discharging compressed air against said film, thereby disrupting the same and discharging it as a mass or cloud, supplementally discharging compressed air upon said mass or cloud and varying the point or points of impact of the supplementally discharged compressed air upon said mass or cloud with respect to the point of emergence 15 of said mass or cloud.
2. That method of applying coating comprising supplying coating material, discharging compressed motive fluid against said coating material, thereby effecting the 20 discharge thereof as a mass or cloud, discharging motive material supplementally upon said mass or cloud and varying with respect to the point of discharge of the mass or cloud the point or points of impact of the supplementally discharged motive fluid, thereby varying the breaking up effect of the said supplemental discharge of motive fluid.
3. That method of applying coating comprising providing a film of coating material, discharging compressed air against said film thereby disrupting the same and discharging it as a mass or cloud, discharging a plurality of streams of compressed air 35 upon said mass or cloud, and varying in a forward or backward direction with respect to the point of discharge of the mass or cloud the points of impact of the supplemental streams of compressed air, thereby 40 varying the breaking up effect of such supplemental streams of air at a given pressure.
4. Means for applying coating comprising means for maintaining a film of coating material, means for causing a motive agent to break through and discharge said film, means to discharge the motive agent supplementally upon the discharged film to transform the latter into a mass having a different cross section, and means to advance or 45 retract with respect to the point of discharge of the film, the point of impact of the supplemental motive agent upon the discharged film, thereby to vary the breaking up effect 55 of the supplemental motive agent.
5. Means for applying coating comprising means to supply coating material, means to subject the same to the action of a motive agent, thereby effecting the discharge of the 60 coating material, means to discharge a motive agent supplementally upon the discharged coating material, and means to change lengthwise of the discharged coating material, the point of impact of the sup-

plemental motive agent upon the said discharged coating material.

6. A tool for applying coating comprising a body having passages for coating material and for a motive fluid under pressure, a member supported by said body and having one or more supplemental motive agent discharge passages in communication with the motive agent supply passage, said member being adjustable upon the tool longitudinally of the axis of the latter, thereby to 75 vary the point of impact of the supplemental motive agent upon the discharge coating material.

7. A tool for applying coating comprising a body having passages for coating material 80 and for a motive fluid under pressure, a member supported upon said body and having one or more supplemental motive agent discharge passages in uninterrupted and continuous communication with the motive 85 agent supply passage, and means for effecting longitudinal adjustment of said member.

8. A tool for applying coating comprising a body having passages for coating material and for a motive agent under pressure, and 90 a member supported upon said body and having one or more supplemental motive agent discharge passages in communication with the motive agent supply passage, said member being adjustable upon the tool in a 95 direction longitudinally of the axis of said tool for the purpose set forth.

9. A tool for applying coating comprising a body having passages for coating material 100 and for a motive agent under pressure, and a member supported upon said body and having one or more supplemental motive agent discharge passages in communication with the motive agent supply passage, said tool body and member having interengaging 105 threaded surfaces permitting longitudinal adjustment of said member.

10. Means for applying coating comprising a body having passages for the coating material and for air under pressure, a substantially cylindrical member 42 supported upon said body and having a plurality of supplemental air passages 43, 44, said body and member having communicating passages 47, 48, 49, said body and member having interengaging threaded surfaces 50, 51 to permit longitudinal adjustment of said member 42.

11. Means for applying coating comprising a body having passages for coating material and for a motive fluid under pressure 120 and a member 42 supported by said body and having one or more supplemental motive agent discharge passages in communication with the motive agent supply passage of the body, said member 42 being capable of longitudinal adjustment with respect to said body without interrupting the

communication between the supplemental motive agent discharge passages in said member and the motive agent supply passage in the body.

5 12. A tool for applying coating comprising a body having passages for coating material and for a motive agent under pressure and a member supported upon said body and having one or more supplemental

motive agent discharge passages in communication with the motive agent supply passage, said member being mounted for circumferential movement and for longitudinal adjustment upon said body.

In testimony whereof I have signed my name to this specification.

HERBERT W. DAY.
